United States Patent Office.

WILLIAM C. KING, OF PITTSBURG, PENNSYLVANIA, ASSIGNOR TO KING, SON & CO., OF SAME PLACE.

Design No. 4,753, dated April 4, 1871.

DESIGN FOR THE ORNAMENTATION OF TABLE-GLASSWARE.

The Schedule referred to in these Letters Patent and making part of the same.

To all whom it may concern:

Be it known that I, WILLIAM C. KING, of Pittsburgh, in the county of Allegheny and State of Pennsylvania, have invented a new and original Design for Table Glassware, of which the following is a specification, reference being made to the accompanying drawings, on which similar letters of reference indicate corresponding parts.

Figure 1 represents the goblet of this design.

Figure 2 represents the same turned one-sixth around.

Figure 3 represents the knob on the dish and bowl covers, seen from above, the balance of the cover being broken away.

Figure 4 is a side view of the same.

The design consists in elevated lines or ridges encircling the goblet, dish, or other article of ware, forming alternate panels and squares, as shown in figs. 1 and 2.

The squares above mentioned are occupied by rosettes, as shown at *a*, figs. 1 and 2, and the long enclosed spaces or panels contain a succession of raised maple leaves overlapping each other and pointing in

opposite directions, or toward the ends of panels, as shown in figs. 1 and 2, the last two leaves being base to base at the center of the panel, and having their stems crossed, as shown at *b*.

A short distance each side of the panel-work above described are two or three other ridges encircling the vessel and forming a border.

The knob shown in figs. 3 and 4 is formed on the covers for the dishes and bowls, and represents a pine cone resting on several maple leaves overlapping each other by the edges, and having their apexes pointed outward from a common center.

The above design is formed on goblets, sugar-bowls, pitchers, spoon-holders, dishes, bowls, and other articles of table-ware by pressure in molds in the usual way.

I claim—

The design for the ornamentation of glassware, as described and shown.

WM. C. KING.
